UNITED STATES PATENT OFFICE.

WILLIAM A. LORENZ, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,127,048.

Specification of Letters Patent.

Patented Feb. 2, 1915.

Application filed September 27, 1910. Serial No. 584,028.

To all whom it may concern:

Be it known that I, WILLIAM A. LORENZ, a citizen of the United States, residing at Hartford, in the county of Hartford and State of Connecticut, have invented certain new and useful Improvements in Type-Writing Machines, of which the following is a full, clear, and exact description, such as will enable others skilled in the art to 10 which it appertains to make and use the same.

This invention relates to typewriting machines and with regard to the more specific features thereof, to improved type actions 15 therefor.

One of the objects of the present invention is to provide a practical and efficient type action for typewriting machines.

Another object is to provide a silently 20 acting type action with an easy dip to the operating key and a prompt return to normal position.

Another object is to provide a type action in which rebounding of the movable 25 parts will be eliminated.

Another object is to provide a simple form of type action which will be cheap to manufacture and easy to install.

A further object is to provide an improved form of universal bar mechanism 30 adapted to be used with the present form of type action although not limited thereto.

A further object is to provide a light but substantial carriage mechanism.

Other objects will be in part obvious and in part pointed out hereinafter.

The invention accordingly consists in the features of construction, combinations of elements and arrangement of parts which 40 will be exemplified in the construction hereinafter set forth, and the scope of the application of which will be indicated in the following claims.

In the accompanying drawings, wherein 45 are shown several of various possible embodiments of the present invention, Figure 1 is a sectional view showing one form of type action in normal position; Fig. 2 is a similar view showing the type-bar in actuated position; Fig. 3 is an enlarged view of a portion of Fig. 2; Fig. 4 is a plan view of the part shown in Fig. 3; Fig. 5 is a

detail sectional view; Fig. 6 is a modification showing one form of arresting means; Fig. 7, is a partial sectional view showing 55 a further modification; Fig. 8 is a view similar to Fig 6, with the action in extended position; and Fig. 9 is a plan view showing the improved form of platen carriage.

Similar reference characters refer to similar parts throughout the several views of the drawings.

While the present invention is illustrated and described with reference to that form of typewriting machines known as "the 65 noiseless typewriter," it is, of course, to be understood that various features herein described and claimed, while particularly adaptable to pressure-operated machines, may be applied to other forms of type actions, and in other connections as well. 70

Referring now to these drawings in detail, and particularly Figs. 1 and 2, 1 represents a platen or paper-roller mounted upon a rod 2, and, in the present case, being preferably provided with a flat metallic platen 3 adapted to receive the compressive or squeezing action exerted upon the paper by type 4 carried by a type member 5. This type member is mounted upon the forward 80 end of a reciprocating type-carrier 6, having rearwardly extending guide legs, the upper one being the longer, and in the form herein shown is provided with a normal or central type with upper and lower case type adjacent thereto. The upper and lower parts of the type member 5 are provided with 85

forwardly projecting type-protecting means 7 which extends slightly in advance of the face of the type 4. In order that the 90 purpose of these type-protecting members may be the more readily understood, it may be explained that in "the noiseless typewriter", as well as some other makes, the type-carriers are arranged radially to the 95

printing point; those type-carriers at the extreme outer edge of the type segment being adapted to move through a vertical plane disposed substantially at an angle of 45° to the printing line. Now, should 100 one type-carrier be actuated by one hand and moved to the printing position while a second type action at the opposite side of the segment is still at the printing posi-

tion, not having been released by the other hand, it will be seen that the type members will contact with one another, to the probable injury of the last actuated type action.

5 Therefore, if the type members are provided with forwardly projecting type-protecting members, such as herein shown, the force of the impact will be taken up by the projections, thereby eliminating any chance of 10 injury to the type faces themselves.

The type-carrier or type-bar 6 is adapted to slide along radially disposed grooves 8 located in a bed-plate 9 mounted on the upper part of the frame of the machine.

15 An upper guide-plate 10 is similarly grooved and engages the upper edge of the type-bar and the rearwardly extending guide leg in such a manner as positively to prevent a tilting motion of the type-carrier 20 when actuated. The lower part of the type-carrier may be cut away, as shown in the drawings, to avoid unnecessary friction, if so desired. In order to prevent the type-bar from tilting sidewise when in extended 25 position, as shown in Fig. 2, a comb member 11 projects upwardly from the bed-plate 9 and engages the sides of the type-carrier in the manner shown in cross-section in Fig. 5. The type-carrier 6 is connected with an actuating key-lever 12 by intermediate mechanism including a toggle cam link 13, which, with an upwardly swinging oscillatory cam member 14, is adapted to form a toggle, shown in extended position in Fig. 2, for 30 positively limiting the movement of the type-carrier, thereby creating a normal printing plane, relatively to which the platen is movable by mechanism such as shown for example in Patent No. 879,107, dated February 11, 1908, to Kidder and Sponsel. This toggle cam member 14 is pivotally mounted at 15 on an adjustable cam block 16 secured to the front wall of the machine. This cam block may be 40 adjusted in the direction of the path of travel of the type-carrier by means of set screws 17 and 18, the former clamping the adjusting block to the frame, while the latter determines the adjusted position. On the 45 upper part of the cam block 16 is pivotally mounted a bell-crank lever or toggle-actuating member 19, the shorter arm of which is connected by means of an adjustable pull-wire 20 with the key-lever 12, while the 50 longer arm carries a roller 21 adapted to form a rolling connection with the oscillatory cam member 14 by engaging a cam slot 22 therein. This cam slot 22 is gradually curved through the larger part of its 55 length and terminates near one end in a sharply deflected cam portion indicated at 60 23. This cam slot is of such a configuration as to cause a gradually increasing rate 65 of movement toward the platen during the

first part of the movement of the key-lever 65 and a gradually decreasing rate of movement, terminating in a compressive or squeezing contact with the paper on the platen, during the latter part of the movement of the key-lever. By this mechanism 70 the rate of movement of the type-carrier toward and from the platen is positively controlled. This cam slot 22 is also provided at each end with an extended portion 75 known as a cam dwell, the curvature of the cam at these points being concentric with an arc struck from the pivotal point of the bell-crank lever as a center. In Fig. 3 the type action is shown in extended position in full lines, the dotted position of the bell-crank lever 19 denoting the extent of additional movement into the cam dwell permitted this part and also the key-lever without 80 in any way affecting the movement of the type-carrier.

85 Referring to Fig. 4 of the drawing, it will be seen that the adjusting block 16 is bifurcated at its forward end and holds the oscillatory cam member 14 therebetween. This cam member has a rearwardly projecting portion or horn 24 which is adapted closely to fit between the sides of the block 16, whereby a tilting motion of the cam is 90 positively prevented. The pull-wire 20, shown in section in this view, also passes 95 between the sides of the adjusting block, thereby insuring a straight vertical movement when the device is actuated.

95 From this construction and arrangement of parts, it will be seen that the oscillatory cam member 14 and connecting link 13 will 100 counterbalance the weight of the pull-wire 20 and the key-lever 12, when returning to normal position. In this manner a more rapid return of the parts to normal position is attained and also the possibility of 105 the type-carrier or other parts of the actuating mechanism rebounding, as might occur in mechanisms where the oscillatory cam member swings upwardly when returning 110 to normal position, is eliminated.

115 The key-lever 12 is pivotally mounted upon a transversely disposed shaft 25, to which is also pivotally supported a universal bar 26 by means of rearwardly extending arms 27. Springs 28 and 28' engage, respectively, the key-lever and the universal bar arms 27 in order to return 120 these parts to normal position. The movement of the universal bar in a downward direction is arrested by means of a pad 29 mounted on a transverse beam 30 located in the frame of the machine, to the forward edge of which is positioned a comb member 31, for guiding the movements of the key-levers, and also a rearwardly bent stop 32 engaging a pad 33 on the upper surface of 125 the universal bar 26, thereby silently to ar-

rest the upward movement of the bar when returning to normal position.

By pivotally mounting the universal bar and key-lever upon the same pivot the friction between the surfaces of the key-levers which oscillate and the universal bar contacting therewith, which reciprocates, is eliminated.

In order that the actuating mechanism interposed between the type-carrier and key-lever may be silently arrested upon its return movement, an abutment 34 provided with silencing means such as a pad 35 is adapted to be engaged by a projecting arm 36 on the oscillatory cam member whereby this part will return to normal position without impact or concussion.

The operation of this modification, it is thought, may be understood from the above description, but it will, nevertheless, be stated, in brief, as follows: When a key-lever is actuated, it not only depresses the universal bar 26, thereby to actuate the escapement mechanism, not herein shown, and space the carriage in the usual manner, but also draws the pull-wire 20 downwardly, thereby oscillating the bell-crank lever 19 to cause the roller 20 carried thereby to traverse the cam slot in the cam member 14 and move the type-carrier forward to the printing position. When the toggle formed by the cam member and link 13 is in extended position, the type will have reached the normal printing plane. It is, of course, to be understood that the platen and the type-members are movable relatively to each other, in order that, when manifolding, the outer sheet may be disposed in the normal printing plane.

Referring now, briefly to Fig. 6, the means for silently arresting the return of the actuating mechanism to normal position comprises a stop member or pad 37 positioned upon the movable link 13 and which is adapted to be engaged by a projecting lug 38 on the oscillatory cam member 14. This will not only silently arrest the parts on return to normal position, but also prevents the rear end of the type-carrier from riding upwardly on its return movement, as a downward pressure will be exerted upon the pad 37 by the cam member when returning to normal position. This same mechanism is shown in actuated position in Fig. 8, and otherwise is substantially the same as the action shown in Fig. 1.

In Fig. 7 is shown a somewhat similar type action, in which the silencing pad is disposed on a forwardly projecting lug 39 secured to the frame of the machine. A heel or the like 40 carried by the link 13 is adapted to engage this pad in the manner herein shown.

In Fig. 9 is shown in plan view the

platen-carriage, in which the platen 3 secured to end plates 41 lies closely adjacent the platen roller or paper roller 1. By securing the platen in this manner, with the concaved face lying adjacent the platen-roller, there will be no tendency for the platen to move upwardly or downwardly from a normal position when struck slightly off center, as illustrated in Fig. 8, the dotted line representing the center of a normal impression, while the type therein shown designates a period normally striking below the center of the printing line. It is thus seen that this invention is adapted to accomplish, among others, the objects above set forth in a practical and efficient manner.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:

1. A typewriter action combining a relatively fixed frame part, an actuating lever pivoted thereto having a short arm normally forwardly extending from the lever pivot and a long arm extending oppositely therefrom, a finger lever, a member connected therewith at its lower end and connected with the short arm of said lever, whereby upon depressing said finger lever said actuating lever will be moved and its long arm elevated, a type carrier adapted to reciprocate, and a power transmitting member having a movement-rate controlling surface and interposed between said type carrier and the actuating lever and operatively connected with the extremity of the long arm of the latter to be impelled thereby upwardly and rearwardly to advance said type carrier, the parts of said action at opposite sides of the pivot of the actuating lever tending to counter-balance each other.

2. A typewriter action combining a relatively fixed part, a link having a connection with said part whereby it may undergo an angular movement relatively thereto, a pressure operating type carrier connected with said link at a point remote from its point of connection with said part, and an actuating lever of the first order, the extremity

of one arm of said actuating lever bearing on said link at a point intermediate said two distanced points whereby at its initial movement the link will swing about said 5 first point as an instantaneous center and its second point will advance at a more rapid rate than the intermediate point.

3. A typewriter action combining a lever supporting part, an actuating lever pivoted 10 at an intermediate point to said part, a finger lever, a pull wire uprising therefrom and pivoted at its upper end to the upper end of said actuating lever, a link having a curved movement-rate controlling surface, 15 and a type carrier connected therewith, the lower end of said actuating lever being connected with said link whereby upon depressing said finger lever, said link will be moved upwardly and rearwardly to advance 20 said type carrier at a variable rate of speed.

4. In a typewriting machine, in combination, a key-lever, a type-bar, a platen with which said type-bar coacts, mechanism between said key-lever and said type-bar including an oscillatory curved member for controlling the rate of movement of said type-bar, said curved member swinging upwardly and rearwardly toward the platen when actuated, and a member operatively 30 connected with said cam member for transmitting motion thereto when the key-lever is depressed, said parts being counterbalanced.

5. In a typewriting machine, in combination, a key-lever, a type-bar, mechanism between said key-lever and said type-bar for transmitting motion from one to the other including an upwardly swinging cam member for controlling the rate of movement of 35 said type-bar, and a member operatively connected with said cam member transmitting motion thereto when the key-lever is depressed, said parts being counterbalanced.

6. In a typewriting machine, in combination, a key-lever, a type-bar, mechanism between said key-lever and said type-bar for transmitting motion from one to the other, including a movement rate controlling member, an actuating lever, and a pull wire, 50 said member adapted partially to counterbalance the weight of said key-lever and pull-wire through the pivot of said actuating lever.

7. In a typewriting machine, in combination, a platen, a type carrier having an increasing, followed by a decreasing, rate of movement toward said platen whereby it prints by pressure in contradistinction to impact, a key-lever, and means for transmitting motion from said key-lever to said type-carrier including an upwardly swinging cam member adapted to control the said rate of movement of said type-carrier.

8. In a typewriting machine, in combination, a platen, a type carrier having an in-

creasing, followed by a decreasing, rate of movement toward said platen whereby it prints by pressure in contradistinction to impact, a key-lever, and means for transmitting motion from said key-lever to said type-carrier including an upwardly swinging cam member, said cam member being so formed as to positively control the said rate of movement of said type-carrier.

9. A typewriter action of a front strike machine, combining a fixed frame portion, a block adjustable thereon, an actuating lever pivoted thereto having a short arm normally extending upwardly and forwardly from the lever pivot and a long arm extending downwardly therefrom, a finger lever, a vertical pull-wire directly connected therewith at its lower end and directly connected with the extremity of the short arm of said lever, whereby upon depressing said finger lever said actuating lever will be moved and its long arm elevated, a type carrier adapted to horizontally reciprocate, and a power transmitting member having a curved movement-rate controlling surface interposed between said type carrier and the actuating lever and operatively connected with the extremity of the long arm of the latter to be impelled thereby upwardly and rearwardly to advance said type carrier.

10. In a typewriting machine, in combination, a type-carrier, a platen with which said type-carrier coacts, a member moving upwardly and rearwardly toward the platen when actuated adapted positively to control the movement of said type-carrier, and actuating means for said member.

11. In a typewriting machine, in combination, a type-carrier, a platen with which said type-carrier coacts, a member moving upwardly and rearwardly toward the platen when actuated adapted positively to control the movement of said type-carrier, and actuating means for said member, said actuating means and member tending to counterbalance one another.

12. In a typewriting machine, in combination, a type-carrier, a platen with which said type-carrier coacts, a key-lever, intermediate mechanism for transmitting motion from said key-lever to said type-carrier including a toggle, and means for swinging said toggle upwardly to extended position.

13. In a typewriting machine, in combination, a type-carrier, a platen with which said type-carrier coacts, a key-lever, intermediate mechanism for transmitting motion from said key-lever to said type-carrier, including a toggle, and a bell-crank lever adapted to engage a portion of said toggle and swing the same upwardly into extended position.

14. In a typewriting machine, in combination, a type-carrier, a platen with which said type-carrier coacts, a key-lever, intermediate mechanism for transmitting motion

- from said key-lever to said type-carrier including a toggle, a bell-crank lever adapted to engage a portion of said toggle and swing the same upwardly into extended position, 5 and an adjusting block to which one end of said toggle is secured, whereby the length of throw of said type-carrier may be adjusted.
15. In a typewriting machine, in combination, a relatively fixed portion of the frame of the machine, a type-carrier, a downwardly moving key-lever, and intermediate mechanism for transmitting motion from the key-lever to said type-carrier including 10 upwardly swinging actuating means for positively controlling the rate of movement of said type-carrier, said actuating means being adjustably mounted on said relatively fixed portion of the frame of the machine 15 and tending to counterbalance said key lever.
16. A typewriter action combining a frame portion, a block mounted thereon and capable of adjustment fore and aft of the machine, an actuating lever pivotally mounted intermediate its ends on said block, a pull wire connected at one end to the forward end of one arm of said lever, a key lever to which the other end of said pull wire 20 is connected, a straight thrust type carrier adapted to reciprocate in a horizontal direction, and a floating member connected at one end to one end of said type carrier and operatively connected at a point remote therefrom with said actuating lever, whereby said floating member is moved upwardly and rearwardly as said key lever is actuated.
17. A typewriter action combining a rigid frame portion, a block mounted thereon adjustable fore and aft in the machine, a link having a connection with said adjustable block whereby it may undergo an angular movement relatively thereto, a horizontally reciprocating type carrier connected with 40 said link at a point remote from its point of connection with said block, and an actuating lever pivoted intermediate its ends, the extremity of the long arm of said actuating lever bearing on said link at a point intermediate said two distanced points whereby at its initial movement the link will swing rearwardly about said first point as an instantaneous center and its second point will advance at a more rapid rate than the 45 intermediate point.
18. A typewriter action combining a fixed frame portion, a block adjustable thereon, an actuating lever pivoted thereto having a short arm normally extending upwardly and forwardly from the lever pivot and a long arm extending downwardly therefrom, a finger lever, a vertical pull wire directly connected therewith at its lower end and directly connected with the extremity of the 50 short arm of said lever, whereby upon de-
- pressing said finger lever said actuating lever will be moved and its long arm elevated, a type member adapted to horizontally reciprocate, and a power transmitting member having a curved movement-rate controlling surface and interposed between said type member and the actuating lever and operatively connected with the extremity of the long arm of the latter to be impelled thereby upwardly and rearwardly to advance said type member.
19. A typewriter action combining a frame portion, a block adjustably mounted thereon, a lever pivotally mounted on said block, a pull wire connected at one end to one arm of said lever, a key lever to which the other end of said pull wire is connected, a type carrier adapted to move in a rearward direction, and a floating member connected to the rear end of said type carrier 80 and operatively connected at a point remote therefrom with said lever, whereby said floating member is moved rearwardly as said key lever is actuated.
20. A typewriter action combining a frame portion, a block adjustably mounted thereon, a link having a connection with said adjustable block whereby it may undergo an angular movement relatively thereto, a straight thrust pressure-operating type 90 carrier connected with said link at a point remote from its point of connection with said block, and an actuating lever pivoted at an intermediate point to said block and having arms of unequal length, the extremity of the long arm of said actuating lever bearing on said link at a point intermediate said two distanced points whereby at its initial movement the link will swing about said first point as an instantaneous center 95 and its second point will advance at a more rapid rate than the intermediate point.
21. In a typewriting machine, in combination, a platen, a type-carrier adapted to contact therewith, a key-lever, intermediate mechanism for transmitting motion from one to the other, a universal bar beneath said key-lever, and an abutment against which said universal bar is adapted to contact silently to arrest the movement thereof.
22. In a typewriting machine, in combination, a platen, a type-carrier adapted to contact therewith, a key-lever, intermediate mechanism for transmitting motion from one to the other, a universal bar beneath said key-lever, a comb member for guiding the movement of said key-lever, and an abutment supporting said comb member adapted to engage and silently arrest the movement of said universal bar.
23. A typewriter action combining a rigid frame portion, a block mounted thereon, a lever having unequal arms pivotally mounted intermediate its ends on said block, a pull wire connected at one end to the shorter arm 130

- 6
- of said lever, a horizontally disposed key lever to which the other end of said pull wire is connected, a pressure-operating type carrier adapted to reciprocate in a horizontal direction, and a floating part connected at one end to the rear end of said type carrier and operatively connected at a point remote therefrom with said lever, whereby said part is moved upwardly and rearwardly as said key lever is actuated.
24. In a typewriting machine, in combination, a platen, a type-carrier, a key-lever, intermediate mechanism for transmitting motion from the key-lever to the type-carrier including an upwardly swinging actuating cam member, and a pad for silently arresting the return movement of said cam member.
25. In a typewriting machine, in combination, a platen, a type carrier, a key-lever, intermediate mechanism therebetween including an upwardly swinging cam member and a cushioning pad positioned below said cam member for silently arresting the same on its downward movement to normal position.
26. In a typewriting machine, in combination, a platen, a type-carrier, a key-lever, intermediate mechanism for transmitting motion from the key-lever to the type-carrier including a toggle, means for swinging said toggle upwardly to extended position, and means for silently arresting the movement of said toggle when returning to flexed position.
27. In a typewriting machine, in combination, a platen, a type-carrier adapted to coact with said platen, a key-lever, cam mechanism connected with said type-carrier and key-lever for positively controlling the movement of said type-carrier comprising a pivotally mounted part, and means for cushioning the return movement of said part to normal position.
28. In a typewriting machine, in combination, a platen, a type-bar adapted to coact therewith, a key-lever, actuating mechanism between the key-lever and type-bar including a toggle cam, and a toggle cam lever, said toggle cam having an upwardly swinging movement when said key-lever is depressed.
29. In a typewriting machine, in combination, a platen, a type-bar adapted to coact therewith, a key-lever, actuating mechanism between said key-lever and type-bar including a toggle cam, an upwardly moving toggle cam lever, and a block on which said parts are mounted.
30. In a typewriting machine, in combination, a platen, a type-bar adapted to coact therewith, a key-lever, actuating mechanism between said key-lever and type-bar including an upwardly moving toggle cam, a toggle cam lever, a block on which said parts are mounted, and means for adjusting said block in the direction of the path of travel of said type-carrier.
31. In a typewriting machine, in combination, a platen, a type-bar adapted to coact therewith, a key-lever, actuating mechanism between the key-lever and type-bar including an upwardly moving toggle cam, an upwardly moving toggle cam lever, a rolling connection between said parts and means for silently arresting the return movement of said parts to normal position.
32. In a typewriting machine, in combination, a platen, a type-carrier adapted to coact therewith, actuating mechanism for said type-bar including an upwardly swinging cam member, a pivotally mounted bell-crank lever, a rolling connection between said lever and said cam member, and means for actuating said lever.
33. A typewriter action combining a fixed frame portion, a lever-supporting block adjustably resting on said frame portion, an actuating lever pivoted at an intermediate point to said block, a finger lever, a pull wire uprising therefrom and pivoted at its upper end to the upper end of said actuating lever, a link, and a type member connected therewith, the lower end of said actuating lever being connected with said link whereby upon depressing said finger lever, said link will be moved upwardly and rearwardly to advance said type member.
34. A typewriter action combining a platen and a fixed frame portion, a block thereon, an actuating lever pivoted thereto having a short arm normally extending upwardly from the lever pivot and a long arm extending downwardly therefrom, a finger lever, a pull wire directly connected therewith at its lower end and directly connected with the extremity of the short arm of said lever, whereby upon depressing said finger lever said actuating lever will be moved and its long arm elevated, a type carrier adapted to move relatively to said platen, and a power transmitting member having a curved movement rate controlling surface and interposed between said type carrier and the actuating lever and operatively connected with the extremity of the long arm of the latter to be impelled thereby upwardly and rearwardly to advance said type carrier.
35. A typewriter action combining a frame portion, a block adjustably mounted thereon, a link having a connection with said adjustable block whereby it may undergo an angular movement relatively thereto, a type carrier connected with said link at a point remote from its point of connection with said block, and an actuating lever pivoted at an intermediate point to said block, the extremity of the long arm of said actuating lever bearing on said link at a point intermediate said two distanced points

- whereby at its initial movement the link will swing about said first point as an instantaneous center and its second point will advance at a more rapid rate than the intermediate point.
36. In a typewriting machine, in combination, a type-bar, a key-lever, intermediate connecting mechanism for actuating the type-bar including an oscillatory cam member, a link connected therewith, and a stop member below said cam member with which said link coacts whereby the return movement of said parts is silently arrested.
37. In a typewriting machine, in combination, a plurality of straight-thrust type carriers having rearwardly extending guideways, and upper and lower guide-plates for said type carriers having a plurality of continuous longitudinal grooves in which guideways of said type carriers are adapted to slide.
38. In a typewriting machine, in combination, a platen, a plurality of pressure-operated straight-thrust type-carriers radially disposed from the printing point on said platen, and upper and lower guide plates for said type-carriers having continuous grooves therein in which said type-carriers are adapted to slide.
39. In a typewriting machine, in combination, a platen, a plurality of pressure-operated straight-thrust type-carriers radially disposed from the printing point on said platen, upper and lower guide plates for said type-carriers having continuous grooves therein in which said type-carriers are adapted to slide, and a comb member associated with one of said plates adapted to engage the sides of said type-carriers.
40. In a typewriting machine, in combination, a platen, a plurality of pressure-operated straight-thrust type-carriers radially disposed from the printing point on said platen, upper and lower guide plates for said type-carriers, having continuous grooves therein in which said type-carriers are adapted to slide, and a comb member associated with said lower guide plate project-
- ing upwardly to engage the sides of said type-carriers to prevent tilting motion 50 thereof.
41. In a typewriting machine, in combination, a key-lever, a straight-thrust type-bar, mechanism therebetween for transmitting motion from one to the other including a 55 pivotally mounted bell-crank lever, a pull-wire connected with one end of said lever and said key-lever, and a member adapted to have an upward movement, said member being operatively connected with the other 60 end of said bell-crank lever.
42. A typewriter action combining a fixed frame portion, a lever-supporting block adjustably secured to the frame portion, an actuating lever pivoted at an intermediate 65 point to said block, a finger lever, a pull wire uprising therefrom and pivoted at its upper end to the upper end of said actuating lever, a floating link, and a type carrier operatively connected therewith, the lower 70 end of said actuating lever being operatively connected with said link whereby upon depressing said finger lever, said link will float upwardly and rearwardly to advance said type carrier. 75
43. A typewriter action combining a frame portion, a block adjustably mounted thereon and capable of adjustment fore and aft of the machine, a lever pivotally mounted intermediate its ends on said block, a pull wire 80 connected at one end to one arm of said lever, a key lever to which the other end of said pull wire is connected, a type carrier adapted to reciprocate in a horizontal direction, and a floating member connected at 85 one end to the rear end of said type carrier and operatively connected at a point remote therefrom with said lever, whereby said floating member is moved upwardly and rearwardly as said key lever is actuated. 90
- In testimony whereof I affix my signature, in the presence of two witnesses.

WILLIAM A. LORENZ.
